The ornamental design for a laser range finder with wind sensor, as shown and described.

DESCRIPTION

FIG. 1 is a right side perspective view of an embodiment of the laser range finder with wind sensor;

FIG. 2 is a left side perspective view of the laser range finder with wind sensor of FIG. 1;

FIG. 3 is a right side elevational view of the laser range finder with wind sensor of FIG. 1;

FIG. 4 is a left side elevational view of the laser range finder with wind sensor of FIG. 1;

FIG. 5 is a top plan view of the laser range finder with wind sensor of FIG. 1;

FIG. 6 is a bottom plan view of the laser range finder with wind sensor of FIG. 1;

FIG. 7 is a front end view of the laser range finder with wind sensor of FIG. 1; and,

FIG. 8 is a rear end view of the laser range finder with wind sensor of FIG. 1.

The broken lines are for illustrative purposes only and form no part of the claimed design.
